UNITED STATES PATENT OFFICE.

DOMER A. BURNS, OF MILLER, ARKANSAS.

COMBINED ROLLER AND HARROW.

1,268,319.

Specification of Letters Patent.

Patented June 4, 1918.

Application filed December 22, 1917. Serial No. 208,371.

To all whom it may concern:

Be it known that I, DOMER A. BURNS, a citizen of the United States, residing at Miller, in the county of Cleburne and State 5 of Arkansas, have invented certain new and useful Improvements in Combined Rollers and Harrows, of which the following is a specification, reference being had to the accompanying drawings.

10 This invention relates to certain improvements in a combined roller and harrow and it is an object of the invention to provide a device of this general character having a novel and improved connection between the 15 roller structure and the harrow whereby the harrow may be adjusted with convenience and facility relative to the roller structure.

It is also an object of the invention to provide a device of this general character having novel and improved means whereby the harrow may be vertically adjusted as the occasions of practice may require.

The invention consists in the details of construction and in the combination and arrangement of the several parts of my improved combined roller and harrow whereby certain important advantages are attained and the device rendered simpler, less expensive and otherwise more convenient 30 and advantageous for use, as will be herein-after more fully set forth.

The novel features of my invention will hereinafter be definitely claimed.

In order that my invention may be the 35 better understood, I will now proceed to describe the same with reference to the accompanying drawings, wherein:

Figure 1 is a view in top plan of a combined roller and harrow constructed in accordance with an embodiment of my invention, the harrow lifting mechanism being omitted;

Fig. 2 is a view in side elevation of the device as herein disclosed;

Fig. 3 is a fragmentary sectional view partly in top plan and partly in section, illustrating the connection between the lifting lever and the rod engaged with the harrow; and

Fig. 4 is a sectional view taken substantially on the line 4—4 of Fig. 2.

As disclosed in the accompanying drawings F denotes a frame preferably rectangular in form and which includes the removable front transverse beam 1 held in applied position through the medium of the bolts 2

or the like, as is believed to be clearly illustrated in Fig. 1.

Coacting with the removable beam 1 is a suitable hitching means 3. As I do not 60 wish to be understood as limiting myself as to the type of hitching means employed, a detailed description and illustration thereof is believed to be unnecessary. The side beams 5 of the frame F are provided at 65 substantially their longitudinal centers with depending bearings 4 affording mounting for the roller R arranged within the frame F.

Straddling the rear portion of the side beams 5 of the frame F are the elongated 70 members 6 in cross section substantially in the form of an inverted U and having their upper intermediate portions forming the racks 7 disposed longitudinally of the side beams 5.

Surrounding each of the members 6 and the adjacent side beam 5 is the sliding member or block 8 and disposed through the upper portion of said member or block 8 is a latch 9 coacting with the adjacent rack 7 80 for holding the member or block 8 against movement longitudinally of the member 6. Coacting with the latch 9 is a conventional operating means 10 mounted upon the upper end portions of the upstanding lever 11 85 also carried by the member or block 8. The upstanding lever 11 affords convenient means whereby the member or block 8 may move longitudinally of the member 6 after the latch 9 has been disengaged from the 90 rack 7.

H denotes a harrow comprising the transversely disposed beams 12 arranged in parallelism and having engaged therewith as at 14 and 14', ground engaging members 95 15 of a conventional type. Each of the beams 12 comprises two sections having their inner ends overlying as at 16 and such overlying end portions are pivotally engaged by the members 17 which are also directed 100 through the beam 18 of predetermined length. Each of the pivot members 14' coacting with the inner or rear beam 14 has its lower portion provided with the tubular head 19 through which the shank 20 of the 105 ground engaging member 15 is directed. It is also to be understood that the shank 20 of each of the ground engaging members 15 underlies the front or forward beam 12. To reinforce the connection in the beam 18, I 110 employ straps 21 pivotally engaged at their outer extremities with certain of the pivotal

members 14' and have their inner extremities overlying the beam 18 and in overlapping relation. The overlapping portions 22 thereof are pivotally engaged with the member 17 coacting with the inner or rear beam 12.

Pivotally engaged with the front or forward end portion of the beam 18 is a clevis 23 having swinging movement in a vertical path, and said clevis 23 is disposed through an eye member 24 extending rearwardly from the lower end portion of an up-right 25 carried by the rear beam 26 of the frame F and positioned at the longitudinal center thereof. Coacting with the upright 25 and the rear beam 26 are the brace members 27.

The upper end portion of the up-right 25 is continued by the forwardly directed extension 28 which serves as a support for 20 the seat S. Suitably engaged with the forward or free end portion of the extension 28 are the downwardly diverging brace members or supports 29 anchored at their lower extremities to the inwardly directed arms 25 30 positioned at the forward ends of the side beams 5 of the frame F. It is also to be stated that the front beam 1 is directly engaged with the arms 30.

Each of the side beams 5 of the frame F 30 rearwardly of the member 6 is provided with an upstanding guide 31 herein disclosed as an eye-member and through which is freely directed a rod 32. The forward end portion of the rod 32 is pivotally engaged as at 33 with the upper portion of the member or block 8. The rear or opposite end portion of the rod 32 is provided with an eye 34 through which is loosely directed a clevis 35 pivotally engaged with 35 the outer end portion of a section of the forward or front beam 12 of the harrow. It is also to be noted that the clevis 35 is movable about a vertical axis.

Pivotally engaged with the rear end portion of the beam 18 and capable of adjustment longitudinally thereof is the upstanding clevis 36 freely disposed through the eye 37 formed at the lower end portion of the upstanding rod 38.

50 M denotes a handle member comprising two separated rigid strips 39 arranged in parallelism and which overlie the opposite faces of the rearwardly disposed plate 40 and pivotally engaged therewith as indicated at 41. The plate 40 is substantially semi-circular in elevation and extends rearwardly from the central portion of the up-right 25. At a predetermined point intermediate the lengths thereof, the strips 39 55 are provided with the opposed outward offset portions 42 between which is arranged an annular or eye member 43 provided with an diametrically opposed trunnions 44 pivotally engaged with said offset portions 42. 60 The rod 38 is loosely disposed through the

annular or eye member 43 and said rod 38 above the handle member M has adjustably secured thereto, the stop member 45 so that normally the rod 38 and the annular or eye member 43 are held against separation. Adjustably secured through the rod 38 below the member M and in close proximity to the eye 37 is a second stop 46. Interposed between the stop 46 and the annular or eye member 43 is an expansible 75 member 47 herein disclosed as a conventional coil spring encircling the rod 38 and which serves to constantly urge the beam 18 downwardly.

Suitably secured between the outer extremities of the strips 39 of the member M is the hand grasp 48 having pivotally engaged therewith the lever 49 of the latch mechanism 50. The mechanism 50 coacts with the segmental rack 51 formed in the 80 periphery of the plate 40 whereby the beam 18 or more particularly the harrow structure may be readily and effectively held at various elevations relative to the ground or other surface upon which the device may 85 be resting or traveling.

The members 6 may be held to the side beams 5 of the frame F in any manner desired, but herein are disclosed holding members or pins 52 which are disposed 90 transversely through such members and coacting beam 5. By adjusting the members or blocks 8 longitudinally of the side beams 5 of the frame F, it will be at once self-evident that any desired angle may be given 95 to the harrow structure and in the event it is not required to use the harrow structure, the same may be readily rendered inoperative by raising the handle member upwardly. I also find it of advantage to provide the rear beam 26 of the frame F at substantially its longitudinal center with a depending member 56 provided at its lower end with a shoe 57 adapted to contact with the ground or other surface which serves to 100 prevent over-balancing of the frame F when the harrow structure H is in elevated position.

From the foregoing description, it is thought to be obvious that a combined roller 115 and harrow constructed in accordance with my invention is particularly well adapted for use by reason of the convenience and facility with which it may be assembled and operated and it will also be obvious that 120 my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the character described com- 130

prising a frame, a harrow structure positioned rearwardly of the frame, slideable members engaged with the side members of the frame and having substantially rectilinear movement, and connections between said slideable members and the opposite end portions of the harrow structure.

2. A device of the character described comprising a frame, a harrow structure positioned rearwardly of the frame, slideable members engaged with the side members of the frame and having substantially rectilinear movement, connections between said slideable members and the opposite end portions of the harrow structure, and means for holding said slideable members against movement.

3. A device of the character described comprising a frame, a harrow structure positioned rearwardly of the frame, slideable members engaged with the side members of the frame, connections between said slideable members and the opposite end portions of the harrow structure, an upstanding member carried by each of the sliding members and means for holding said sliding member against movement.

4. A device of the character described comprising a frame, a harrow structure positioned rearwardly of the frame, slideable members engaged with the side members of the frame, connections between said slideable members and the opposite end portions of the harrow structure, and means for connecting the harrow structure with the frame at a point substantially midway of the harrow structure.

5. A device of the character described comprising a frame, a harrow structure positioned rearwardly of the frame, slideable members engaged with the side members of the frame and having substantially rectilinear movement, connections between said slideable members and the opposite end portions of the harrow structure, and means for lifting the harrow structure.

6. A device of the character described comprising a frame, a harrow structure positioned rearwardly of the frame, slideable members engaged with the frame, connections between said slideable members and the opposite end portions of the harrow structure, a member extending rearwardly from the frame and overlying the harrow structure and mounted for movement in a vertical plane, and connection between said member and harrow structure whereby said harrow structure may be raised or lowered.

7. A device of the character described comprising a frame, a harrow structure positioned rearwardly of the frame, slideable members engaged with the frame, connections between said slideable members and the opposite end portions of the harrow structure, a member extending rearwardly from

the frame and overlying the harrow structure and mounted for movement in a vertical plane, a connection between said member and harrow structure whereby said harrow structure may be raised or lowered, and means for normally holding said member against movement.

8. A device of the character described comprising a frame, a harrow structure positioned rearwardly of the frame, slideable members engaged with the frame, connections between said slideable members and the opposite end portions of the harrow structure, a member extending rearwardly from the frame and overlying the harrow structure and mounted for movement in a vertical plane, a connection between said member and harrow structure whereby said harrow structure may be raised or lowered, and means coacting with the harrow structure and the member for constantly urging the harrow structure downwardly.

9. A device of the character described comprising a frame, a harrow structure positioned rearwardly of the frame, slideable members engaged with the side members of the frame, connections between said slideable members and the opposite end portions of the harrow structure, and coacting means carried by said side members of the frame and the slideable members for holding said slideable members against movement.

10. A device of the character described comprising a frame, members secured to the side members of the frame and provided with racks, members surrounding said last named members and the side members of the frame and mounted for sliding movement, a latch mechanism carried by each of the sliding members and coacting with the adjacent rack for holding said sliding member normally against movement, a harrow structure positioned rearwardly of the frame, and connections between the sliding members and the opposite end portions of the harrow structure.

11. A device of the character described comprising a frame, a beam positioned rearwardly of said frame and having an end portion loosely engaged with the rear portion of said frame substantially midway thereof, beams disposed transversely of the first named beam and extending beyond opposite sides thereof, each of said beams comprising sections having their inner end portions pivotally engaged with the first named beam, ground engaging members provided with shanks pivotally engaged with the sections of the transverse beam, and members connected to the outer end portions of the transverse beams and having adjustable connection with the side portions of the frame.

12. A device of the character described comprising a frame, a beam positioned rearwardly of said frame and having an end

portion loosely engaged with the rear portion of said frame substantially midway thereof, beams disposed transversely of the first named beam and extending beyond 5 opposite sides thereof, each of said beams comprising sections having their inner end portions pivotally engaged with the first named beam, ground engaging members provided with shanks pivotally engaged with 10 the sections of the transverse beam, members connected to the outer end portions of

the transverse beams and having adjustable connection with the side portions of the frame, and means carried by the frame and coacting with the rear end portion of the first named beam for elevating the same.

In testimony whereof I hereunto affix my signature in the presence of two witnesses.

DOMER A. BURNS.
